UNITED STATES PATENT OFFICE.

WINFIELD B. CASWELL, OF EAST ORANGE, NEW JERSEY.

DAVIT AND MEANS FOR OPERATING THE SAME.

1,258,316.

Specification of Letters Patent.

Patented Mar. 5, 1918.

Application filed February 21, 1917. Serial No. 150,075.

To all whom it may concern:

Be it known that I, WINFIELD B. CASWELL, a citizen of the United States of America, residing at East Orange, county of Essex, 5 State of New Jersey, have invented certain new and useful Improvements in Davits and Means for Operating the Same, of which the following is a specification.

This invention relates to davits for life-boats and means for operating the same.

More particularly the invention relates to davits and means for operating the same from inboard position to outboard position and vice versa, comprising unitary means 15 for actuating and controlling both davits whereby the speedy operation of the life-boat under all serviceable conditions at sea is insured and injury to the life-boat and persons therein is precluded.

20 In the preferred forms of the invention, the operating means for the davits are constructed and arranged to be placed into position without alteration or removal of the davits from their usual mounting and supports.

25 In accordance with the preferred forms of the invention, the two davits are actuated and controlled by means of a single crank, or equivalent, and the operating means for the respective davits are constructed and arranged to prevent faulty or 30 improper movements of either during the operation of the other in the movement of the life-boat into lowering position over the side of the ship. In such preferred forms

35 of the invention, I employ a pawl or equivalent, attached to each davit and arrange a set of ratchet teeth or equivalent, for such pawls and actuate the sets of ratchet teeth by suitable actuating means. As one form of such actuating means I employ a single operating shaft controlled by the crank, and arrange suitable means, preferably worm gearing, for actuating the sets of ratchet teeth, the said pawls being positioned in re- 40 versed relationship to one another, whereby one pawl only, and thereby one davit only, at a time is under actuation by the crank while the other pawl slips relative to its set of ratchet teeth and thereby the other 45 davit is under indirect operation by the crank. Preferably, I arrange the pawls to be on the outboard sides of the respective davits when the latter are in full inboard position, in which case the pawls point to- 50 ward each other. When it is desired to

move a life-boat from outboard to inboard, the pawls are then reversed in the positions respectively attained by them upon completion of the aforesaid movement of the life-boat to full outboard position. 60

The invention attains further advantages in that the operating means of the davits are locked one against the other in all positions and held under control against either fore and aft or athwart-ship movement 65 caused by lash.

Further features and objects of the invention will be more fully understood from the following description and accompanying drawings, in which— 70

Figure 1 is a top plan view of the operating means;

Fig. 2 is a side elevation of Fig. 1;

Fig. 3 is a top plan diagrammatic view of one form of the invention showing the 75 life boat at a stage of movement from inboard to outboard position; and

Fig. 4 shows the same with the life boat in full outboard position.

Referring to Figs. 1 and 2, the davit 1 is 80 provided with a unit of operating means arranged and constructed in correspondence to the unit of operating means for the davit 2 and conjointly operated by means of the unitary power applying means controlled by 85 hand crank 3. Onto the davit 1 is fixed the support ring 4 having a boss to which is pivotally supported the pawl 5. The support ring 4 is preferably of split construction, shown as formed of halves connected by the 90 bolts 6. The support ring 4 is fixed to the davit 1 by means of the key 7, or equivalent, and the set bolt 8, the head 9 of which serves to retain the pawl 5 in position on the said boss. 95

The set of ratchet teeth 10 is mounted in proper relation to coöperate with the pawl 5 and as one form of mounting means I have shown the ratchet teeth 10 as an annulus cast integrally with the annulus worm 100 gear 11.

The clearance between the inner periphery of the ratchet annulus 10 and the davit 1 enables the combined ratchet annulus 10 and worm gear 11 to be slipped over the head 105 or suspension end of the davit and along the davit until the proper position for the combined ratchet and worm annulus is attained.

If desired, the combined ratchet and worm annulus 10, 11, may be constructed as a split 110

ring, connected and locked in position by bolts, similar to the support ring 4, as aforesaid.

In suitable relation to said worm gear 11 5 I provide means for rotating such gear and as a preferred form thereof I have shown the worm 13 fixed on the shaft 14, to which the crank 3 is also affixed. I prefer the worm gearing as shown, in that the same is 10 self locking and self-adapted to distortion of parts incident to use.

Referring now to the davit 2, I have provided the similar support ring 15 fixed to the davit 2 by means of the key 16 and 15 clamped by the bolts 17. I have also provided the annular set of ratchet teeth 18 driven by the worm gear 19, in turn driven by the worm 20 mounted on the operating shaft 14. The pawl 21 is pivotally carried 20 on the boss of the support ring 15 in suitable relation to the set of ratchet teeth 18. Preferably, I provide for one or more eye joints 22 in the operating shaft 14 between the driving means 13 of davit 1 and the 25 driving means 30 of davit 2, whereby a limited extent of lost motion is afforded between the respective driving means 13, 20, to compensate for distortion of the operating parts incident to use, temperature variations and 30 the like. Preferably, the pawls 5, 21 are located on the outboard sides of the davits when the latter are in full inboard position, to thereby prevent tampering with the pawls by unauthorized persons.

35 Referring now to Fig. 3, as well as Figs. 1 and 2, we will assume the pawl 5 and the pawl 21 to be positioned as indicated in Fig. 2, *i. e.*, toward each other, and that the life boat 23 and davits 1, 2, are positioned full 40 inboard of the ship. Upon application of power either manually, or under motive power, the operating shaft 14 is then rotated say in clockwise direction (as viewed facing the left hand crank 3 as shown in 45 Fig. 1), whereupon the pawl 5 will be caught in a tooth of its ratchet annulus 10 and force the davit 1 to be directly actuated in counter-clockwise direction of rotation whereby the davit 1 will be turned toward 50 outboard and the end 24 of boat 23 moved outboard. Such movement of davit 1 causes the davit 2 to be indirectly turned for a certain arc of movement in the same direction of rotation, by reason of the span cable 26 55 and also the suspension relationship of the boat 23 to both davits. Upon further outboard direct turning of davit 1, the davit 2 will then be indirectly turned in the opposite direction of rotation, until the relative 60 position of the davits indicated by Fig. 3 is attained, thereupon the direction of turning of the crank 3 is reversed, whereupon the davit 1 is now directly actuated in clockwise rotation, *i. e.*, more and more outboard, 65 and the davit 2 indirectly turned through

the certain arc of movement first in one and then in the reverse direction of rotation, until both davits attain full outboard position, as indicated in Fig. 4. Under normal conditions the approximate length of 70 the said certain arc of rotation is about twenty degrees.

A similar operation of the two davits but under reversed direct and indirect actuation ensues upon turning the crank 3 75 initially in counter-clockwise rotation when moving the life boat from inboard to outboard position. Under whichever initial direction of turning of the crank, the pawls 5, 21, upon full outboard position of the 80 life-boat, will have been moved to their inboard position and point away from one another.

When it is desired to move the life-boat 85 from outboard to inboard position, the pawls 5, 21 are each set manually or otherwise into their respective opposite positions, *i. e.*, into the relationship of pointing toward each other, whereupon the crank 3 is turned in either initial direction of rotation and subsequently in the opposite direction of rotation, until full inboard position of the life-boat, or davits, is attained.

In the above described form of the invention, the power is applied by means of 90 a single device and unitary control of both davits is obtained at all times. Also, it will be noted that the mechanical means employed enables but a single sea-man to effectually move a life-boat filled to full capacity to lowering position under all conditions at sea possible for launching a life-boat.

It will be noted that during the several 105 stages of operation of the actuating mechanism, only one davit at any stage is under direct actuation by the power applying means while at such stage the other davit is indirectly operated but under full control of the power applying means.

Under conditions of a list of the ship, and either fore and aft or athwart-ship lashing, the davits are under control at all times, whether the life-boat is allowed to move under gravity with the list or actuated 115 against the list. At all stages of the positions of the davits, one davit is locked against the other to prevent precipitate movement of the life-boat or faulty direction of turning of one davit relative to the 120 other.

For the purpose of providing compensating means for bending or distortion of the davits incident to use, I prefer to mount the worms 13, 20 on a plate 31 having a 125 collar 32 loosely passing around each davit and fitted within the guides 33 of the base 34 secured by bolts or otherwise to a suitable support, whereby compensation of any bend or distortion of a davit is taken up by 130

W. B. CASWELL.

DAVIT AND MEANS FOR OPERATING THE SAME.

APPLICATION FILED FEB. 21, 1917.

operating said davits, said individual means comprising a pawl and an annular ratchet member having an inner opening materially greater than the cross sectional area of a davit, and common means for operating said individual means.

15. The combination with a plurality of davits, of individual means for respectively actuating said davits, one of said individual means comprising a member providing free movement of said member for any desired extent at will in one direction but direct actuation of a davit in the opposite direction, and common means for operating said individual means.

16. The combination with a plurality of davits, of individual means for respectively actuating said davits, each of said individual means comprising a member providing free movement of said member for any desired extent at will in one direction but direct actuation of a davit in the opposite direction, and common means for operating said individual means.

17. The combination of a plurality of davits, of individual means for operating said davits, each of said means comprising a member providing free movement of a davit in one direction but positive actuation in the same direction, and common means for operating said individual means.

18. The combination of a plurality of davits, of individual means for operating

said davits, each said means comprising a member providing free movement of a davit in one direction but positive actuation in the same direction, and common means for operating said individual means, said common means being rotative and effectively operable at will in either direction of rotation.

19. The combination of a plurality of spaced rotative supports, a device carried by said supports, means for mounting said supports to move said device to a plurality of predetermined positions, individual means for operating said supports, and common means for operating said individual means, said common means being rotative and effectively operable at will in either direction of rotation for moving said device continuously from one of said predetermined positions to another of said predetermined positions.

20. The combination of a plurality of spaced rotative supports, individual means for rotating said supports, each of said individual means comprising a member providing free movement of a support in one direction but positive actuation in the same direction, and common means for operating said individual means.

In testimony whereof I have signed this specification this 15th day of February, 1917.

WINFIELD B. CASWELL.
